UNITED STATES PATENT OFFICE.

THOMAS HEATH AND CHARLES H. SUCH, OF PROVIDENCE, RHODE ISLAND, ASSIGNEES TO R. BLACKINTON & CO., OF NORTH ATTLEBORO, MASSACHUSETTS, A FIRM.

DESIGN FOR A HANDLE FOR SPOONS, FORKS, OR SIMILAR ARTICLES.

SPECIFICATION forming part of Design No. 36,932, dated May 31, 1904.

Application filed May 6, 1904. Serial No. 206,762. Term of patent 7 years.

To all whom it may concern:

Be it known that we, THOMAS HEATH and CHARLES H. SUCH, citizens of the United States, residing at Providence, in the county of Providence and State of Rhode Island, have invented a new, original, and ornamental Design for the Handle of a Spoon, Fork, or Similar Article, reference being had to the accompanying drawings.

Figure 1 is a view of the obverse side of the handle embodying our design, and Fig. 2 is a reverse view of the same.

What we claim as new, and desire to secure by Letters Patent, is—

The ornamental design for the handle of a spoon, fork or similar article, as shown.

THOMAS HEATH.
CHARLES H. SUCH.
